UNITED STATES PATENT OFFICE

WILLIAM E. WINE, OF TOLEDO, OHIO

CAR-DOOR MECHANISM

Application filed October 25, 1923. Serial No. 670,720.

This invention relates to a door mechanism for railway cars or the like, and its principal object is to provide an improved construction whereby hinged car doors may be closed and securely held in such position. Another leading object of the invention is to provide advantageous means whereby a removable lever may be used to pry the door shut.

With these and other objects in view, the invention consists in the construction, combination and arrangement of parts herein-after described and claimed.

In the accompanying drawings which illustrate a preferred form of the invention,—

15 Figure 1 is a fragmentary side elevational view, showing a portion of a railway car equipped with a door mechanism constructed in accordance with the principles of the present invention.

20 Figure 2 is an end elevation of the construction, looking in the direction of the arrow A, Fig. 1.

Figure 3 is a detail sectional view on the line B—B, Fig. 1.

25 Figure 4 is a detail sectional view on the line C—C, Fig. 1, parts of the door supporting mechanism being omitted.

30 Figure 5 is a diagrammatic view showing the relation of a pair of doors as used in twin hopper car construction.

Figure 6 is a view diagrammatically illustrating the relation of the door mechanism to a car of the twin hopper type.

The car chosen for explaining the invention 35 is of the twin hopper type illustrated in my prior Patent No. 1,431,506 wherein two doors are arranged transversely of the car. The doors are spaced apart slightly and are held in a definite spaced relationship by a door spreader which forms a stiffening beam for supporting the doors. The car side includes a hopper side sheet 1 disposed in an inclined plane so that the width of the car adjacent the rail at the hoppers is less than that at a point further above the rail. Attached to the hopper side sheet is a sloping floor sheet 2, the hopper discharge opening being defined in part by an edge of the side sheet 1 and the lower edge of the floor sheet 2. There are 40 two of these hoppers at each end of the car,

one being located at each side of the center sills of the car. A door 3 is provided for each discharge opening. These are hinged to the car body at points near the uppermost edges of the discharge openings. This construction is well known in the art.

The edge of the side sheet 1 defining the discharge opening of the hopper is outwardly offset at 4 to form a shoulder 5 against which the door 3 may seat when closed. The door is also provided with an outstanding marginal flange 6 which extends along the outer edge of the door and forms with the outermost edge 7 of the offset portion of the side sheet 1 a pair of substantially parallel flanges. The plane of the portion 7 of the side sheet 1 may be slightly inclined outwardly from the general plane of this sheet, so as to guide the door into proper position. A stiffening angle 8 may be secured to the lower edges of the floor sheet 2 in the customary manner.

The door spreader is shown as consisting of a transversely extending channel iron 9 which connects both doors 3 at one end of the car. The outer end of the channel 9 may be coped out, as at 10, to provide a space for the outstanding flange 6 of the door and also to permit the end of the door spreader to project beyond the edge portion 7 of the hopper side sheet which extends outwardly beyond the plane of the shoulder 5 and beyond the general plane of the door when the latter is in closed position. The door spreader is secured to the outer faces of the doors 3, preferably by means of rivets, and at each of its ends is provided with a door supporting arm 11 rigidly affixed to the spreader and extending slightly beyond the end thereof. In the present embodiment of the invention the door supporting arm 11 is formed as a short length of angle iron secured to the web of the channel 9 by means of rivets 12 passing through one leg of the angle iron member. The other leg of the angle iron 11 is secured to the door plate by means of a rivet 13 passing through the latter. The door arm 11 is bent outwardly or offset from the plane of the door 3 so as to extend over the flange 6 and also over the edge 7 of the hopper side sheet 1.

per side sheet 1. At its outer end the upstanding leg of the angle iron 11 is preferably disposed so as to form an acute angle with the plane of the door 3 and an acute angle with the plane of the web of the door spreader or channel 9, thus enabling the outer end of the door arm 11 to present an extended bearing seat or ledge for cooperation with the door supporting hook, shortly to be described, and also serving to minimize any creeping movement of the hook tending to cause it to be accidentally disengaged from the door arm.

In order to hold the door 3 in closed position a door supporting hook 14 is pivotally mounted on the hopper side sheet 1. For this purpose, a bracket base 15 is secured to the outer face of the hopper side sheet behind the offset 4 therein. Secured to the member 15 so as to be spaced therefrom a sufficient distance for receiving the door supporting hook 14 and the cam 17 by which said hook is locked in door supporting position, is a plate member 16 which overlies the pivot end of the hook and the cam 17. The members 15 and 16 of the bracket may be secured to the car by rivets 18 which also serve to hold the hook and pawl in pivotal relationship to the bracket. The base 15 of the bracket is arranged to space the hook 14 outwardly from the general plane of the hopper side sheet 1 a sufficient distance to enable the hook to overlie the offset portion 4 of the sheet, so that said hook may operate in a plane parallel with the sheet 1 and just outside of the edge 7 thereof. A guide bar 19 is preferably employed to prevent undue lateral play of the hook 14 on its pivot in a direction transversely of the car. This guide bar, which is affixed to the offset portion of the side plate 1 by means of rivets 20, is suitably spaced from the edge 7 of the plate 1 to provide a way or recess of sufficient length to accommodate the normal pivotal movements of the hook 14. By these means the tendency of the hook to slip along the face of the door arm which it engages is reduced and injury to the hook pivot and to the bracket upon which said hook is mounted is prevented.

Door supporting mechanisms of this character are preferably capable of preliminarily supporting the door in a partially closed position from which it may be forced completely shut. In the present embodiment of the invention provision is made for temporarily supporting the door in partially closed position by forming the hook 14 with a ledge 21 which, like the ledge 22 for holding the door in fully closed position, is adapted to engage the upstanding flange of the angle iron door arm 11.

The present invention includes means for forcing the door from a partially closed position to a final position of closure. For this

purpose a bracket 23 is affixed to the side sheet of the hopper, as by means of rivets 24, said bracket preferably being formed as an angle iron having one flange 25 lying against the hopper side sheet 1 and having its other flange or leg 26 projecting outwardly from said hopper sheet. The angle iron bracket 23 is bent outwardly to pass over the offset 4 of the hopper side sheet and its outer end extends beyond the edge 7 of said sheet and also beyond the flange 6 of the door. The outer end of the bracket is preferably so positioned that some fixed portion of the door may bear against it to arrest slippage of the door downwardly away from its hinged pintles. In the present instance one flange of the channel iron door spreader 9 is adapted to bear against the outermost end of the angle iron bracket 23 to effect this purpose.

The leg 25 of the bracket 23 is provided at a point beyond the edge of the door flange 6 with an aperture 27 through which a removable lever 28 may be inserted for the purpose of prying the door shut, said aperture in the bracket 23 affording a shoulder or fulcrum for the lever. When inserted through the aperture 27 the removable lever 28 is adapted to bear against the outer face of the door 3, occupying an operating position as indicated in dotted lines in Figs. 2 and 4. In some instances, however, it is preferable that the door prying lever be entered in a different direction, or that more power should be available for forcing the door to closed position. Accordingly, the outstanding leg of the angle iron door arm 11, which in effect is an extension of the door spreader 9, is provided with a hole 29 through which the removable lever 28 may be inserted, said hole providing a seat for the lever. Immediately beneath the aperture 29 a similar hole 30 is formed in the outstanding leg 26 of the angle iron bracket 23, said hole providing a fulcrum for the lever. The hole 30 is preferably spaced a short distance from the hole 29, so that enough movement of the lever will be available to propel the door to closed position. In the present construction the spacing of the lever receiving apertures is conveniently effected by taking advantage of the downstanding flange of the channel 9 as a member to bear against the angle iron bracket 23. When a door prying lever, such as is indicated at 28, is inserted through these alined openings a powerful leverage is available to force the doors shut.

It will be appreciated by those skilled in the art that if for any reason the door should become stuck, jammed or frozen in fully closed position so that it fails to open upon an unlocking rotation of the hook 14, it may be readily pried open by a reversal of that force normally applied to move the door to closed position when the lever occupies the position shown in Figure 1.

As indicated in Fig. 2, the construction permits convenient manipulation of the lever free from the interference of any structures along the right of way lying outside of the car clearance line D.

5 I claim:—

1. A door mechanism for railway cars including, in combination with a door hinged to the car body, a stiffening member secured to the outer face of the door, said member extending beyond an edge of the door and embodying a seat for a door supporting member, an aperture in the stiffening member, and a bracket affixed to the side of the car and having an aperture substantially in alignment with the aperture in said stiffening member, said apertures being adapted simultaneously to receive a removable door prying lever.

20 2. A door mechanism for railway cars including, in combination with a door hinged to the car body, a door-supporting arm carried by the door and extending outwardly beyond an edge of the latter, a door-supporting member pivoted to the car adjacent the door supporting arm and adapted to engage said arm, and a bracket affixed to the car body adjacent the said edge of the door and the said door-supporting arm, said bracket being 25 of angular section having one flange lying against the car side and another flange outstanding from said side, said flanges being disposed at an angle to each other, and said bracket being furnished with a fulcrum 30 adapted to accommodate a removable door prying lever.

3. A door mechanism for railway cars including, in combination with a door hinged to the car body, a door-supporting arm carried by the door and extending outwardly beyond an edge of the latter, a door-supporting member pivoted to the car adjacent the door-supporting arm and adapted to engage said arm, and a bracket affixed to the car body 40 adjacent the said edge of the door and supporting arm, said bracket being formed of a member of angular section having one flange lying against the car side and secured thereto through said flange and having another flange 45 outstanding from the car side, said flanges being disposed at an angle to each other, and one of said flanges having a hole adapted to provide a fulcrum for a removable door-prying lever.

55 4. A door mechanism for railway cars including, in combination with a door hinged to the car body, a door supporting arm carried by the door and extending outwardly beyond an edge thereof, a door-supporting member pivoted to the car adjacent the door-supporting arm and adapted to engage the latter, and a bracket affixed to the car body adjacent the said edge of the door and adjacent said door-supporting arm, said bracket being 60 formed of a member of angular section hav-

ing one flange lying against the car side and secured thereto through said flange and having another flange outstanding from the car side at an angle to the plane of the latter, and said bracket having a hole in said outstanding flange adapted to receive a removable door-prying lever.

5. A door mechanism for railway cars including, in combination with a door hinged to the car body and having an arm extending beyond one of its edges, of a member pivoted to the car body and adapted to supportingly engage said arm, a bracket affixed to the car body and adapted to form a stop for the said arm to arrest slippage of the door away from its hinge pintles, and aligned shoulders formed on said arm and said bracket to cooperate with a removable door-prying lever.

6. A car door mechanism including, in combination with a door hinged to the car body, a door-supporting member pivoted to the car side adjacent an edge of the door and adapted supportingly to engage a portion of the door, a bracket affixed to the car side and providing a pivotal support for the said door-supporting member, and a member of angular section affixed to the car side and projecting beyond the door, said member having apertures adapted to receive a removable door-prying lever in a plurality of different positions.

7. A railway car having a hinged door, a hopper with a discharge opening therein, a portion of said opening being defined by an edge of one of the side sheets of the car, said edge being outwardly offset from the main portion of the said side sheet in such manner as to form a seat for the adjacent edge of the door, the door having an arm extending outwardly beyond the line of said offset, a door supporting member pivoted upon the said side sheet behind the offset therein and arranged to swing parallel with the plane of the said side sheet and over the offset portion thereof into supporting engagement with the said door arm, and a guide mounted upon and spaced from the said offset portion of the side sheet and arranged to overlie the said door-supporting member.

8. In a car door mechanism, the combination with a hinged door, of means adapted to be engaged by a removable lever for moving said door, said means involving a member carried by the door having a portion forming a seat for said lever, and a member carried by the car body having a portion forming a fulcrum for said lever, the lever engaging portions of said members when the lever is in operative association therewith always being disposed one above the other in vertically spaced relation in all operative positions said lever may assume so as to permit said lever to extend upwardly away from the said lever engaging portions of the members, and means movable with respect to said fulcrum for supporting said door in closed position.

9. In a car door mechanism, the combination with a hinged door, of means adapted to be engaged by a removable lever for moving said door, said means involving a member carried by the door having a portion forming a seat for said lever, and a member carried by the car body having a portion forming a fulcrum for said lever, the lever engaging portions of said members when the lever is in operative association therewith being disposed one above the other so as to permit said lever to extend upwardly away from the lever engaging portions and to have a plane of operation less inclined to the vertical than to the horizontal, and means for supporting said door in closed position.

10. In a car door mechanism, the combination with a hinged door, of means for cooperating with a removable lever adapted to transmit force for moving said door, said means involving a member carried by the door having a portion forming a seat for the said lever, and a member carried by the car body having a portion forming a fulcrum for said lever, the lever engaging portions of said members when the lever is in operative association therewith being disposed in spaced relation along the outer edge of the door between the hinge axis and the opposite free edge of the door so as to permit the end of the lever engageable by the operator to extend upwardly away from the said lever engaging portions and to permit it to operate in a plane substantially parallel to adjacent portions of the car side, and means for supporting said door in closed position.

11. In a railway car having a hopper provided with a lading discharge opening, the combination with a hingedly mounted door for closing the opening, the door being movable to open position under the influence of gravity, of means for cooperating with a removable lever to force the door to closed position, said means including a member secured to the hopper side adjacent the discharge opening thereof affording a fulcrum for the removable lever, and a member carried by the door and projecting beyond a side edge thereof, the projecting portion of said member affording a seat for said lever, the said lever cooperating portions of said members being normally vertically spaced and being arranged to permit said lever to operate in a plane substantially parallel with the adjacent side of the hopper.

12. In a railway car having a hopper provided with a lading discharge opening, the combination with a hinged door for closing said opening, the door being movable to open position under the influence of gravity, of mechanism for supporting the door in closed position involving an arm secured to the door and projecting beyond a side edge thereof, and a hook pivotally mounted on the hopper side having a plurality of ledges co-

operable with said arm to support the door in a partial position of closure and in a final position of closure, said arm having a portion affording a seat for a removable lever employed for forcing the door from partially to finally closed position and a bracket secured to the hopper side and projecting beyond the lading discharge opening thereof below the said door arm, said bracket affording a fulcrum for the removable lever.

13. In a car door mechanism, the combination with a hinged door, of movable means operatively interposed between said door and the car body for supporting said door in closed position, and a fulcrum member carried by the car body projecting laterally beyond said door supporting means, said fulcrum member being adapted to cooperate with a removable lever adapted to apply force to said door at a point laterally outward of the door supporting means, whereby said door may be forced to closed position by said lever.

In testimony whereof I affix my signature.
